DESIGN FOR A NEGLIGEE

Violet Giovagnoni, New York, N. Y.

Application July 30, 1947, Serial No. 140,602

Term of patent 7 years

(Cl. D3—26)

To all whom it may concern:

Be it known that I, Violet Giovagnoni, a citizen of the United States, residing in New York city, in the county of New York and State of New York, have invented a new, original, and ornamental Design for a Negligee, of which the following is a specification, reference being had to the accompanying drawing, forming part thereof.

Fig. 1 is a front view of a negligee, showing my design, and

Fig. 2 is a rear view thereof.

The characteristic feature of my design resides in the combination on the collarless negligee disclosed of the specific rounded reveres, edged in contrasting quilted piping, in association with rounded pockets below the waistline, having similarly piped openings and a three strand belt also of quilted piping which matches the other trim, all as shown.

I claim:

The ornamental design for a negligee, substantially as shown and described.

VIOLET GIOVAGNONI.
